UNITED STATES PATENT OFFICE.

PHILIP L. REHDER, OF BAYVIEW, IDAHO.

FISHERMAN'S HAT.

Application filed December 10, 1926. Serial No. 153,831.

My present invention relates to an improved fisherman's hat designed especially for use in carrying hooks and tackle for use by fishermen. The primary object of the 5 invention is the provision of means by which the hooks and tackle of various kinds may be carried by the fisherman where they are readily accessible when needed. The invention contemplates the use of a specially 10 formed band adapted either as a hat band forming part of the hat or as an annular band adapted to be slipped over the crown of the hat and retained in position over the band of the hat. The band is of the fold- 15 able type and is designed to form an annular pocket in which the leaders may be wrapped, or other parts of the fisherman's equipment may be enclosed therein. Means are also provided for accommodating hooks and flies 20 and for carrying them in convenient position where they are readily accessible when required for use. As is well known by fishermen when the leaders are coiled in a small compass and carried in that manner in order 25 to render them in condition for use, it is necessary to soak the leaders in water over night in order that they may be straightened 30 for use. By utilizing the foldable band as a pocket or enclosure for the leaders, the necessity for soaking and straightening out the leaders is eliminated, and they are ready for use when withdrawn from the enclosure or 35 pocket.

The invention consists in certain novel 35 combinations and arrangements of parts as will be hereinafter more fully set forth and claimed.

In the accompanying drawings, I have 40 illustrated a complete example of my invention wherein the parts are combined and arranged according to the best mode I have so far devised for the practical application 45 of the principles of my invention.

Figure 1 is a perspective view of a hat 45 embodying my invention;

Fig. 2 is a perspective view of the hat 50 shown in dotted lines, and the features of my invention illustrated in full lines;

Fig. 3 is an enlarged detail sectional view 55 of a portion of a hat showing the relation thereto of the band and flap; and

Fig. 4 is a detail perspective view showing the means of attaching and carrying a 60 fly and hook.

In carrying out my invention, the leaders 55 or a line indicated by the letter L are illustrated as carried within an annular band which may be a converted hat band, and the band comprises an inner annular fold 1 and an outer annular fold 2, the latter being 60 adapted to turn up as indicated in Fig. 1. The ends 3 of the outer fold are provided with snap fasteners 4, and it will be apparent that after the leaders have been put in place and the outer fold of the band turned 65 down, and the ends 3 secured by the fasteners 4, the folded band forms a pocket for enclosing these leaders and protecting them from the weather. The leaders are wrapped 70 or coiled uniformly over the inner fold, and are readily accessible when the outer fold has been turned back. An elastic portion 5 of sufficient length is interposed in the foldable band to insure a snug fit of the band 75 over the hat, and it will be apparent that when the band is slipped down over the crown, the band will be retained in correct position by the snug fit over the hat, of which the crown is indicated as 6 and the 80 brim as 7.

In addition to the annular foldable band for carrying the leaders, I employ an upright flap 8 attached at the exterior of the hat with its lower edge secured at 9 to the inner fold of the annular band. At its upper end this flap is provided with a snap fastener 10 which coacts with a complementary member on the exterior of the hat crown. The flap is of a triangular shape, and conforms to the exterior shape of the 90 hat and lies against the hat.

Near the upper end of the flap a pad 11 of felt or other suitable material is secured in which the hooks 12 are carried, and the flies 13 of the hooks extend downwardly and 95 their looped ends 14 are secured in spring retaining clips 15 of a metal strap 16. The felt pad 11 is stitched or otherwise secured at the upper end of the flap, and the metal strap 16 is secured near the lower edge of 100 the flap and parallel with the pad 11. The spring clips 15 are preferably integral with the strap 16, and the clips may be struck up from the metal of the strap by suitable tools. The spring clips retain the looped ends 14 of 105 the flies to maintain the several flies in proper position, but the flies and hooks are readily detachable when wanted. The flies

and hooks are carried between the inner side of the flap and the outer side of the crown of the hat and are thus protected.

As an auxiliary hook and fly holder, I may 5 use a flap 17 which as shown is rectangular in shape and has its lower edge attached to the inner side of the foldable band, preferably at the point opposite the flap 8. This auxiliary flap also carries its hooks and eyes 10 at its inner side and they lie against the exterior face of the hat crown.

It will be apparent that these elements or 15 features of my invention may be used as a part of a hat and embodied in the hat structure, or the device of the invention may be utilized as an attachable and detachable accessory for the fisherman, and when used by a woodsman, the device provides convenient

means for carrying a fishing line with the leader and flies without necessity for any 20 other equipment.

Having thus fully described my invention, what I claim as new and desire to secure by Letters Patent is:—

The combination of an annular, longitudinally foldable hat band for fisherman's use, 25 including an inner fold, an outer fold having separable fastening devices on its adjoining ends for coaction with complementary devices on the inner fold, said folds 30 adapted to form a pocket for leaders, and said leaders adapted to join the adjoining ends of the annular band when it is in place on a hat.

In testimony whereof I affix my signature.

PHILIP L. REHDER.
